UNITED STATES PATENT OFFICE.

AUGUSTE JEAN PARIS, JR., OF BRADFORD, PENNSYLVANIA.

PROCESS OF CLEANING AND REFINING DISTILLATES OF PETROLEUM.

1,405,156.

Specification of Letters Patent. Patented Jan. 31, 1922.

Application filed September 28, 1917. Serial No. 193,624.

To all whom it may concern:

Be it known that I, AUGUSTE JEAN PARIS, Jr., a citizen of the United States, residing in Bradford, county of McKean, and State 5 of Pennsylvania, have invented a certain new and useful Process of Cleaning and Refining Distillates of Petroleum, of which the following is a specification.

This invention is a process of treating the 10 distillates of petroleum, and, more particularly, those ranging from the lighter gasolines to illuminating oils, both inclusive, with a view to purifying them so completely as to render them ideal for use in internal 15 combustion engines, or for other purposes exacting high quality distillates.

As is well known, the so-called "water white" oils on the market are distillates of petroleum which have been purified by the 20 commonly and extensively employed "acid-alkali" process. This process, however, is tedious and comparatively expensive, and yields its best results only in the hands of experts. Furthermore, it is practically impossible to obtain distillates by this process entirely free from the chemical agents employed or the mechanically entrained water.

The products resulting from applicant's 30 process are purer and more uniform than the "water white" oils, and, moreover, the process is expeditious, efficient and economical.

Speaking generally, the present process embodies, in its substantial entirety, the compression of the vapors of the distillates to be 35 refined, in conjunction with a suitable gas, preferably in a compression cylinder, and in the presence of an oil purifying agent. The compressed mixture is then cooled or refrigerated for the purpose of condensing and 40 separating out the resulting purified hydrocarbons.

The purifying agent which it is preferred to use is glycerine, and the gas employed is preferably an inert gas, such as nitrogen or 45 hydrogen. The gas not only serves as a carrier of the vapors, but, also, assists in the vaporization of the petroleum in the compression cylinder. The invention, however, is not restricted to the employment of glycerine as the purifying agent, nor to the use 50 of the specified gases.

The pressures employed in the compression cylinder may range from 25 pounds to 350 pounds, provided, in all cases, the tempera-

ture therein, which may be regulated in various ways, is not permitted to reach a point which would result in any cracking of the particular distillate under treatment.

In the preferred manner of practicing the process, the gas employed, after condensing out the hydrocarbons therefrom, may be returned to the system for reuse, any loss of gas, through leakage or otherwise, being compensated for by introducing additional gas into the system. This necessitates a variation in pressure in parts of the system. That is to say, a main regulating valve is employed, the pressure on one side of which may range from 25 to 350 pounds, i. e., the pressure in the compression cylinder, where- 70 as the pressure on the other side of the regulating valve may range say from atmospheric to 50 pounds pressure. The condensation of the hydrocarbons from the mixture may be effected by either expanding the mixture or refrigerating it externally, or by a combination of both methods.

The distillate or gas, or both, may, if desired, be heated, cooled or refrigerated before compression and the purifying agent 80 may be mixed with the distillate and gas before or during compression.

Features of the process, other than those adverted to, will appear from the herein-after detailed description and claims, read in conjunction with the accompanying drawing. The drawing illustrates a general form 85 of apparatus which I have successfully employed in practicing the invention, but the construction shown therein is to be regarded 90 as typical, only, since various other forms of apparatus may also be employed.

Referring to the drawings, which illustrate the entire apparatus in elevation, and more or less diagrammatically, A is a compression cylinder, into which the oil distillate may be introduced through a branch pipe a, leading from a main oil pipe b. Gas is admitted to cylinder A through pipe c, and, if desired, instead of introducing the oil directly into the compressor, it may be fed to gas pipe c, through pipe d, and thus introduce the commingled gas and distillate together. In this event, it may be found desirable to insert an oil trap e in pipe line c 105 in order to trap out any surplus oil.

Connected with gas pipe c is the gas main f, from which the system is initially sup-

plied with gas, and from which additional supplies may be taken from time to time to replenish that lost by leakage or otherwise.

B is a tank containing the purifying agent, such as glycerine, turkey-red oil, lubricating oil, or castor oil, said agent being fed to compression cylinder A through pipe g, in which is inserted a heater or cooler C, for heating or refrigerating the purifying agent as desired.

An outlet pipe h from the compression cylinder leads, through a branch pipe i, to tank B containing the purifying agent, whereby the purifying agent contained in 15 the compressed mixture may be trapped out for reuse. An exit pipe j, for the compressed mixture of gas and oil vapors, leads from tank B to a condenser C' of any well known type, and in which the bulk of the 20 oil vapors are condensed. The condensate may be drawn off through pipe k, or may be allowed to flow, along with the gas, through pipe l into trap D, from which it may be drawn through pipe m. The gas, after 25 condensing out therefrom the bulk of the purified oil vapors, passes out of trap D, through exit pipe n, into a second condenser E, which is preferably cooled to a temperature lower than that which obtains in condenser C', whereby the residuary oil vapors 30 are condensed. They may be drawn from the condenser through pipe o. It will be understood, of course, that additional condensers may be employed, should it be found necessary or desirable.

The gas, freed from oil vapors, escapes from condenser E, through pipe p, through the main pressure regulating reducing valve p', whence it returns, through an interchangeable heater or cooler F, into gas pipe c, for reuse. Exit gas pipe p, as stated, is provided with the relief or poppet valve p' for regulating the pressure within the system to the desired degree, the pressure on 40 one side thereof is high, and on the other side considerably lower, whereby the oil-free gas may be returned to the system for reuse.

Condensers C' and E may be cooled by a 50 current of water, or other refrigerant, which enters the system through pipe q, passes through condenser E, thence through pipe r into condenser C', and flows off therefrom through pipe s.

It will be understood that the system is 55 provided with any suitable number of pressure gages, as t, t' and t'', thermometers u and u', gages, such as v, safety or relief valves x x', and various manually operable valves, and other accessories incidental to carrying out processes wherein temperatures, pressures, etc., must be controlled.

Having fully described the apparatus, its mode of operation and the manner of carrying out applicant's process therein will be

readily understood, but it may be briefly described as follows.

The mixture of oil distillate or distillates, gas and purifying agent having been obtained in compression cylinder A, in one of the ways described, said mixture is compressed, whereupon it passes off through pipe h into tank B, wherein the purifying agent is trapped out for reuse. When the purifying agent has absorbed impurities to such extent as to render its further use undesirable or inefficient, it may be withdrawn from tank B, through pipe w, purified, and again used.

The mixture of gas and oil vapors, freed from the purifying agent, passes off through pipe j and enters condenser C', wherein substantially all the oil vapors are condensed. The condensate may be drawn off through pipe k, or be allowed to enter trap D, whence it may be drawn off through pipe m. The gas, carrying any of the oil vapors or purified distillate, not separated in condenser C' or trap D, passes out through pipe n into condenser E, where said residuary vapors or distillate, if any is carried by the gas, is separated. The gas, substantially free of oil vapor, is returned through pipe p, through valve p' whereby it is preferably reduced in pressure, for another cycle of operations.

If glycerine or turkey-red oil are used as the purifying agent, they will not only remove tarry vapors, cracked paraffins and other impurities from the distillates under treatment, but, possessing hygroscopic properties, they remove aqueous vapors also. Castor oil and lubricating oil, however, are not of a hygroscopic character, although they are suitable purifying agents in other respects.

It will be understood, of course, that the process may be modified as to details and in the use of equivalents and equivalent operations, without departing from the spirit of the invention, the scope of which is commensurate with the foregoing general description and the appended claims.

Having thus fully described the invention, what I claim as new, and desire to secure by Letters Patent, is:

1. The process of cleaning and refining the distillates of petroleum which consists in charging a gas with such distillates by compressing the gas in conjunction with the vapors of said distillates and in the presence of an oil purifying agent, and subsequently separating the purified distillates from the gas and purifying agent.

2. The process of purifying petroleum distillates which consists in compressing them in the presence of a gas and an oil purifying agent, whereby the gas becomes charged with oil vapors from said distillates, cooling the mixture to condense out the puri-

fied hydrocarbons, and thereafter recompressing the gas in the presence of further oil distillates and an oil purifying agent and repeating the specified cycle of operations.

3. The process of purifying petroleum distillates which consists in compressing them in the presence of a gas and an oil

purifying agent, whereby the gas becomes charged with oil vapors from said distillates, 10 separating the oil purifying agent from the compressed mixture, and thereafter separating the purified hydrocarbons from the gas.

In testimony whereof I have signed my name to this specification.

AUGUSTE JEAN PARIS, Jr.
